UNITED STATES PATENT OFFICE

91,374

DESIGN FOR A COVER FOR A BOX, CARTON, OR THE LIKE

Louis Tichnor, Newton, Mass., assignor to Tichnor Brothers, Inc., Cambridge, Mass., a corporation of Massachusetts

Application April 1, 1933. Serial No. 47,670

Term of patent 3½ years

To all whom it may concern:

Be it known that I, Louis TICHNOR, a citizen of the United States, and a resident of Newton, county of Middlesex, and State of Massachusetts,
have invented a new, original, and ornamental
Design for a Cover for Boxes, Cartons, or the like, of which the following is a specification, reference being had to the accompanying drawing forming part thereof.

The drawing is a perspective view of my cover design.

I claim:

The ornamental design for a cover for a box, carton, or the like as shown.

LOUIS TICHNOR.
